UNITED STATES PATENT OFFICE.

WILLIAM HOLCROFT, OF CHESTER, PENNSYLVANIA.

LOOM.

SPECIFICATION forming part of Letters Patent No. 743,723, dated November 10, 1903.

Application filed September 8, 1902. Renewed September 18, 1903. Serial No. 173,731. (No model.)

To all whom it may concern:

Be it known that I, WILLIAM HOLCROFT, a citizen of the United States, and a resident of the city of Chester, in the county of Delaware and State of Pennsylvania, have invented certain new and useful Improvements in Looms, of which the following is a specification.

My invention relates to improvements in looms; and the object of my invention is to furnish means for perfectly equalizing the tension upon the warp-threads during all the movements incident to the opening and closing of the shed.

15 The warp-threads in a loom are stretched very tightly, almost up to their breaking-point in fact, and when they are further stretched by the heddles in order to form a shed for the passage of the shuttle it is not unusual for breakages to occur, causing much trouble and loss of time in repairs.

In passing from the yarn-beam to the cloth-beam the warp-threads pass over a whip-roller, and at the whip-roller the threads 25 change direction, and it is at this point that I prefer to place my equalizing device, making use of the whip-roller as one member thereof. Instead of having the whip-roller a stationary fixture, as is usual, I mount it or 30 its substantial equivalent in movable bearings, which move inward as the shed is opening, so as to increase the operative length of the threads, and which move outward when the shed is closing, so as to decrease the operative length of the threads, sufficiently to 35 equalize the tension upon them. In other words, to fully equalize the tension on the threads the equalizing device should be moved only during the opening and closing of the 40 shed. During the time that the shed is fully open or fully closed the equalizing device should be idle. If this were not the case, the threads would be when the shed is closed unduly stretched and when the shed is fully 45 opened unduly slackened.

In the accompanying drawings, forming part of this specification, and in which similar characters of reference indicate similar parts throughout the several views, Figure 1 is a 50 diagrammatic sectional side elevation of a loom fitted with my improvement; Fig. 2, a front elevation of the whip-roller.

a is the frame of the loom; *b*, the lay; *c*, the yarn-beam; *d*, the cloth-beam; *f g*, the heddles; *h*, the main shaft, which drives connecting-rod *i*, which operates the lays. All of these parts are of the usual construction and will not need detailed description.

j is a gear-wheel carried on shaft *h*, which gears with and drives a gear-wheel *k*, fast upon a shaft *l*.

m is a gear-wheel fast upon shaft *l*, which meshes with and drives a gear-wheel *n*, fast upon a shaft *o*, which is furnished with cranks *p*, which drive connecting-rods *r*, which are connected to arms *s*, pivoted to the frame *a* at *t* and which carry at their upper ends the whip-roller *u*. The gear-wheels *m* and *n* are so proportioned that the latter makes one complete revolution for each complete beat 70 of the lay or sword *b* or for each complete revolution of the main shaft *h*.

In the loom shown in the drawings the yarn passes from the yarn-beam *c* over the whip-roller *u*, thence through the heddles *f g*, 75 through the head *v* of the lay *b*, over the take-up roller *w* to the cloth-beam *d*. The warp-yarns are, as usual, stretched very tightly, and the mechanism shown is so arranged that when the heddles *f g* separate the warp-threads 80 to open the shed for the passage of the shuttle the upper ends of the arms *s* and the whip-roller are moved inward, thus slackening the threads by reducing the angle formed on their passage from the yarn-beam to the take-up 85 roller to an extent to compensate for the additional strain caused by the movements of the heddles. When the shed is closing, the shaft *o* and crank *p* are in position to cause the rod *r* to move the upper end of levers *s* 90 and whip-roller *u* outward, thus tightening the threads as the strain of the heddles is lessened.

If the whip-roller were rocked back and forth with a regular motion, an undue tension 95 would be put upon the warp-threads when the shed is closed, and an undue slackening of the threads would occur when the shed was opened. As the object of my invention is to at all times maintain an equal tension upon 100 the threads, I rock the whip-roller intermittently—that is, when the shed is opening and the threads are being stretched by the heddles I cause the whip-roller to move inwardly,

thus increasing the operative length of the threads; but as soon as the shed is fully opened I arrest the motion of the whip-roller and do not move it again until the shed is once more 5 in motion. The next movement of the shed is a closing one, and as soon as it commences I rock the whip-roller outward and continue this movement and the consequent tightening of the threads until the shed is fully closed, 10 when I again arrest the movement of the whip-roller until the shed commences to open, when the whip-roller commences to again move inward. By these movements I at all 15 times maintain an equal tension upon the warp-threads.

In order to accomplish the above results, the gear *m* is an interrupted gear, so that the driving of the shaft *o* and crank *p* will only take place during the opening or closing of 20 the shed. During the time that the shed remains fully opened or fully closed the gear *n*, shaft *o*, crank *p*, and connected parts are at rest; but as soon as the shed commences to open or close the gear *n* commences to be 25 driven by gear *m* to rock the whip-roller in or out to lengthen or shorten the shed, as may be necessary to equalize the tension upon the threads, and this movement continues until the shed is fully opened or fully closed, 30 when the teeth on the gear *m* leave the teeth on gear *n*, and the movement of this latter gear comes to a stop, which is insured by a pawl 1 engaging a detent 2 in the hub of gear *n* or by other suitable means.

35 In the drawings the lower ends of the arms *s* are shown furnished with slots *x* to permit a sliding attachment to be made between them and the connecting-rods *r*, of which there are preferably two, one at each side of the machine.

Having thus described my invention, I claim as new and desire to secure by Letters Patent—

1. The combination with a loom, of means, 40 driven from the main shaft, operating synchronously with the movements of the shed,

that is, following the movements of the warp-threads when opening and closing, and ceasing to move during the entire time that said threads are fully opened to form a shed for 45 the passage of a shuttle or fully closed to permit the operation of the lay, for equalizing the tension upon the warp-threads.

2. The combination with a loom, of a whip-roller over which the warp-threads pass, 50 means for carrying said whip-roller so that it may be rocked back and forth in the direction of the warp-threads, and means for rocking said roller inward during the opening of the shed, for rocking it outward during the 55 closing of the shed, and for bringing it to a full stop during the time that the shed is open for the passage of the shuttle or closed for the operation of the lay, said rocking means being actuated positively in both directions from 60 the main shaft of the loom.

3. The combination with a loom, of a roller extending across said loom and over which the warp-threads pass, arms pivoted to the frame of the loom in one of the ends of which said 70 roller is journaled, a connecting-rod one end of which is secured to a crank and the other end of which is secured to said arms, said crank, and means, driven by the main shaft of the loom, for intermittently driving said 75 crank.

4. The combination with a loom, of a whip-roller, arms pivoted to the frame of the loom in which said roller is journaled, a crank adapted to make one revolution for each complete beat of the lay, a shaft upon which said 80 crank is carried, a connecting-rod connecting said crank and arms, a gear-wheel upon said crank-shaft, an interrupted gear for driving said gear-wheel, and gears, driven by the 85 main shaft of the loom for driving said intermittent gear.

WILLIAM HOLCROFT.
